(57) **CLAIM**

The ornamental design for a faucet and cross handle assembly, as shown and described.

DESCRIPTION

FIG. 1 is a left-front perspective view of an embodiment of a faucet and cross handle assembly according to the present invention;

FIG. 2 is a front elevational view of the faucet and cross handle assembly of FIG. 1;

FIG. 3 is a rear elevational view of the faucet and cross handle assembly of FIG. 1;

FIG. 4 is a right side elevational view of the faucet and cross handle assembly of FIG. 1 and is a mirror image of the left side of the faucet and cross handle assembly of FIG. 1; and, FIG. 5 is a top plan view of the faucet and cross handle assembly of FIG. 1.

The broken lines contained in the Figures are for illustrative purposes only and form no part of the claimed design.
